UNITED STATES PATENT OFFICE

123,330

DESIGN FOR A FRONT FENDER FOR A VEHICLE

Ronald J. Waterbury, Birmingham, Mich., assign-
or to General Motors Corporation, Detroit,
Mich., a corporation of Delaware

Application March 5, 1940, Serial No. 90,699

Term of patent 7 years

To all whom it may concern:

Be it known that I, Ronald J. Waterbury, a citizen of the United States and a resident of Birmingham, county of Oakland, and State of Michigan, have invented a new, original, and ornamental Design for Front Fender for a Vehicle, of which the following is a specification, reference being made to the accompanying drawing, forming a part thereof.

Figure 1 is a top plan view of a front fender for a vehicle showing my new design.

Figure 2 is a side elevational view of the fender.

Figure 3 is a front elevational view of the fender.

I claim:

The ornamental design for a front fender for a vehicle, as shown.

RONALD J. WATERBURY.
